UNITED STATES PATENT OFFICE.

OTTO C. SCHOENWERK, OF PHILADELPHIA, PENNSYLVANIA, ASSIGNOR TO BUDD WHEEL COMPANY, OF PHILADELPHIA, PENNSYLVANIA, A CORPORATION OF PENNSYLVANIA.

MILL FOR ROLLING TAPERED DISKS.

Application filed November 22, 1921, Serial No. 516,937. Renewed October 9, 1924.

To all whom it may concern:

Be it known that I, Otto C. SCHOENWERK, a citizen of the United States, residing at Philadelphia, Pennsylvania, have invented 5 certain new and useful Improvements in Mills for Rolling Tapered Disks, of which I declare the following to be a full, clear, and exact description.

This invention relates to an improved mill 10 for rolling tapered disks. The invention relates, more particularly, to a new and improved machine which may be utilized in the rolling of square or rectangular blanks, along radial lines from the centre to the 15 periphery of the blank, in order to cause the periphery of the blank to approach a circle and to taper the blank symmetrically with respect to the centre thereof.

In the application for United States Letters Patent for a machine and method for 20 rolling tapered disks, Serial No. 308,548, filed July 3rd, 1919, by Edward G. Budd and Emil Ibach, there is described and 25 claimed a machine and method by means of which a substantially square blank of uniform thickness may be converted into a substantially circular blank which is tapered from the centre to the periphery, by rolling the square blank successively along a plurality of different radii extending from the 30 centre of the blank to its periphery. The present invention has to do with improvements upon the machine disclosed in said prior application and it relates to an improved mill for use in carrying out certain 35 steps of the method or process of rolling tapered disks set forth and claimed in said prior application.

One of the objects of my invention is to 40 provide means for preventing the clashing or striking together of the working faces of the rolls as the blank or blanks pass from between them.

Another object of my invention is to provide 45 means whereby the pressure is gradually shifted from the working faces to other portions of the roll at predetermined points in the revolution of the rolls so that, when the blank or blanks leave the rolls, the working faces are not under pressure and are held spaced from each other.

A further object of my invention is to provide a mill for rolling tapered disks comprising a pair of cooperating rolls having 50 eccentric working faces and collars rolling

on each other and provided with cooperating cams acting to separate the working faces at predetermined intervals.

Further objects, and objects relating to details and economies of construction and 60 operation, will definitely appear from the detailed description to follow. My invention is clearly defined and pointed out in the appended claims. A structure constituting a preferred embodiment of my invention is 65 illustrated in the accompanying drawings, forming a part of this specification, in which:

Fig. 1 is a view in front elevation of a pair of rolls embodying my invention. 70

Fig. 2^A is a section through the central portions of the rolls, on the line A—A of Fig. 1, showing the rolls in position for insertion of the blanks.

Fig. 2^B is a section through end portions 75 of the rolls, on the line B—B of Fig. 1, showing the parts in position corresponding to that of Fig. 2^A.

Fig. 3^A is a section on line A—A of Fig. 1, through the central portions of the rolls, 80 showing the rolls in such position that the working faces have just engaged the central portions of the blanks.

Fig. 3^B is a section on the line B—B of Fig. 1 but showing the parts in position corresponding to that of Fig. 3^A. 85

Fig. 4^A is a section through the central portions of the roll, on line A—A of Fig. 1 but showing the parts in the position they occupy when the blanks have been partially 90 rolled and the high points of the cams are in contact.

Fig. 4^B is a section, on the line B—B of Fig. 1, but showing the high points of the cams in contact with each other corresponding to the position of the parts in Fig. 4^A. 95

Fig. 5^A is a section through the central portions of the rolls, on line A—A of Fig. 1, but showing the parts in the position they occupy as the blanks leave the rolls. 100

Fig. 5^B is a section, on line B—B of Fig. 1, but showing the parts in position corresponding to the position of the parts in Fig. 5^A.

Fig. 6 is a section through one of the inserts, taken on the line 6—6 of Fig. 1. 105

Fig. 7 is another section through the insert taken on the line 7—7 of Fig. 1, and

Fig. 8 is another section through the insert, taken on the line 8—8 of Fig. 1. 110

In the drawings, the same reference numerals refer to the same parts throughout the several views and the sectional views are taken looking in the direction of the arrows at the ends of the sectional lines.

In carrying out the method or process of rolling tapered disks disclosed in the pending application of Budd and Ibach, to which I have referred, the eccentric working faces on the rolls have been provided by means of inserts rigidly fastened in the body portions of the rolls and usually made of chilled steel castings, so that they will stand up under the very great pressure to which they are submitted. In connection with the operation of this method or process, I have discovered that, when the blanks pass from between these working faces, the rolls, which have been separated by the blanks, suddenly move toward each other and the inserts strike or clash against each other with results which are sometimes very injurious to the working faces of the rolls. My invention comprises means for preventing this striking or clashing together of the inserts or working faces. I accomplish this by gradually removing the pressure upon the working faces, before the blanks pass from between them, and gradually shifting the pressure from the working faces to collars on the rolls which are normally in rolling contact with each other. In carrying out my invention, I provide a pair of cooperating rolls mounted in a frame with the upper roll under pressure and the rolls driven in the usual manner. The mounting of these rolls is all in accordance with the usual rolling mill practice. Each of these cooperating rolls I may provide with a pair of collars, which are normally in rolling contact with each other, and with eccentrically disposed working faces which are so positioned with reference to the axis of these rolls that, when the faces engage a blank or blanks, the contacting collars are forced away from each other so that the rolling pressure is transmitted from one working face, through the blank or blanks, to the other working face. As the rolls revolve, the blank or blanks gradually pass between the rolls in contact with the working faces. I provide the collars with eccentric portions, for instance, cams fixed in the collars, which contact with each other and are so formed and positioned that they engage each other before the blanks pass from between the working faces so that the pressure is gradually shifted from the faces to the collars and the blanks are relieved of pressure before they pass from the rolls.

In the drawing, I have illustrated the cooperating rolls of a rolling mill constituting one embodiment of my invention. There are two of these rolls, 10, each of which comprises a body portion, 11, eccentrically dis-

posed with reference to the axis of the roll, and cylindrical collars, 12, at the ends of the body portion. These rolls may be mounted in a framework and driven and pressure applied to them in accordance with the most approved rolling mill practice and I have not shown these details as they form no part of my invention. The body portion, 11, of each roll, is provided with a recess, 13, in which there is set an insert, 14, which may be secured in place by the clips, 15, which are fastened to the body portion, 11, by the bolts, 16. These inserts are preferably made of chilled steel so as to withstand successfully the very great pressure to which they are subjected in use.

Each insert, 14, has a portion raised above the base thereof and forming the working face of the roll. In this case, the working face comprises a portion, 17, which is adapted to engage the portions of the blank around the center thereof, so as to grip the blank firmly between the rolls, and a central portion, 18, which is segment-shaped as shown in Fig. 1, and comprises the portion between the dot and dash lines in that view. This portion, 18, is slightly concave, as I will point out hereinafter more fully. This segment-shaped portion, 18, is surrounded by the beveled, edge portions, 19 and 20, as shown in Fig. 1 and Figs. 6, 7 and 8. The insert, 14, is set in the body, 11, of the roll, so that the working face projects slightly beyond the cylindrical surface defined by the two collars, 12, at the ends of the roll. This surface is indicated in Figs. 2^A, 3^A, 4^A and 5^A, by the dot and dash circle. The insert, 14, is set in the roll so that the working face thereof is eccentric to the axis of the roll so that the distance from the axis of the roll to the working face gradually increases from the portion, 17, to the beginning of the beveled portion, 19. As I have indicated above, the segment-shaped portion, 18, of the working face, is slightly concave, being ground to form a concave surface, the axis of which extends transversely to the axis of the roll. In Figs. 6 and 7, the line C—C indicates a true plane and shows the amount of concavity or divergence of the upper surface of portion, 18, from a true plane. The insert is beveled, at 21, at the front edge of portion, 17, and a notch, 22, is provided to accommodate the ends of the tongs. The features of construction, which I have described so far in this specification, are not of my invention and I have described them merely to make the relation of my invention to these parts perfectly plain.

In each cylindrical collar, 12, I provide a recess, 23, upon the base of which there is positioned a wedge, 24. Upon this wedge, there is secured within the recess, 23, a cam, 25, the high point of which projects slightly above the cylindrical surface of the

collar. A block, 26, is welded to the collar, 12, against one end of the cam, so as to form a shoulder which will take the large endwise thrust exerted by the cam under the heavy pressures to which it is subjected. The cam is retained in place by the screws, 27 and 28, as shown, for instance, in Fig. 2^B.

The operation of my invention will appear from a consideration of Figs. 2^A, 2^B, 10 3^A, 3^B, 4^A, 4^B, 5^A and 5^B. These views are in pairs and represent sections through the working faces of the rolls and through the collars. Figs. 2^A and 2^B represent the rolls 15 in the position they occupy when the blanks are inserted between them at the beginning of the rolling operation. In Fig. 2^A the blanks, 29, which are preferably square blanks of uniform cross section, are shown held at their centers by the tongs, 30, in the 20 space between the body portions, 11, of the roll. Referring to the companion view, Fig. 2^B, it will be seen that at this time the cylindrical collars, 12, are in contact with each other and hold the rolls in this spaced relation and, because of the eccentricity of the 25 body portions of the rolls, there is sufficient space provided to permit the easy insertion of the blanks and tongs. The rolls are turning in the directions indicated by arrows in 30 these views. In Figs. 3^A and 3^B the position of the rolls is shown at the point when the working faces begin to engage the blanks, 29, and it will be seen that the portions, 17, of the working faces are just 35 engaging the central portions of the blank. Inasmuch as these working faces project slightly beyond the cylindrical surfaces defined by the collars, 12, and indicated in the dot and dash lines in Fig. 3^A, the rolls are 40 separated so that the collars, 12, are no longer in contact with each other, as shown in Fig. 3^B, and the pressure is transmitted from the working face, 17, of the upper roll, through the blanks, 29, to the working face 45 of the lower roll. As the rolls continue to revolve in the direction indicated by the arrows, the working faces will exert a rolling pressure upon the blanks to decrease the thickness thereof and cause the periphery to approach in shape, the arc of a circle. 50 Figs. 4^A and 4^B show the position of the rolls after they have continued their movement to practically the end of the rolling operation and it will be noticed that the blank 55 has been elongated and tapered, as shown in Fig. 4^A. The blanks have not, however, passed as yet from between the working faces and it will be observed that, if it were not for the presence of my invention, when 60 the blanks, 29, pass from between the working faces of the rolls, the upper roll would drop suddenly so that the inserts would strike or clash violently against each other with undesirable results. However, while the inserts have been moving toward each

other and acting on the blanks, the cams, 25, have also moved towards and into engagement with each other and, at the instant when the parts are in position shown in Figs. 4^A and 4^B, the high points of the cams, 25, are in contact with each other and relieve the working faces of the pressure, since the curve with which the working face drops away from the high point is more abrupt than the curve from the high point of the cam, 25, to the cylindrical surface of the collar, 12. The result is that the pressure is gradually shifted from the working faces to the collars and the blanks are relieved of pressure while they pass from between the working faces. Referring to 75 Figs. 5^A and 5^B, the blanks are shown completely free of the rolls and it will be seen that the cams, 25, gradually permit the rolls to resume the normal position in which the cylindrical collars, 12, are in rolling contact with each other. 80

I believe that the foregoing description of the operation of this machine makes my invention very clear. By providing the 90 cams, 25, in the collars, 12, I provide means which prevent the striking of the working faces together, as the blanks leave the rolls, and instead of the sudden movement of the rolls toward each other, which would otherwise result, I have provided means which permit this movement to take place gradually. I have described a specific roll construction in which the working faces are provided on the inserts and are formed in a 95 peculiar manner, but my invention is not to be restricted to a combination in which the working faces are formed as described. My invention will find utility in many situations where the working faces of the rolls are formed differently. I have found that the use of cams inserted in the collars is 100 desirable because the cams may be made of harder material than the rest of the collar, if desired. This is not essential, however. The elevation of the cam may be changed by removing the cam, 25, and substituting a 105 different wedge, 24, for the one in place. These particular details of mounting of the cam may be varied, however, without departing from the broad spirit of my invention. 110

I am aware that the construction illustrated may be changed and altered in many particulars without departing from the 115 broad spirit of my invention and, therefore, I claim my invention broadly, as indicated by the appended claims.

Having thus described my invention, what I claim as new and desire to secure by Letters Patent is:—

1. In an apparatus of the character specified, the combination of a pair of cooperating rolls provided with working faces so disposed with reference to the roll axis as to 120

separate the rolls when the working faces engage a blank, whereby to exert pressure on said blank, and interengaging means on said rolls maintaining the rolls separated during a predetermined portion of their revolution to relieve the pressure on said blanks.

2. In an apparatus of the character specified, the combination of a pair of cooperating rolls provided with portions normally in rolling contact with each other and working faces so disposed with reference to the roll axis as to separate said contacting portions when the working faces engage a blank, thereby exerting pressure on said blank, said contacting portions being so formed as to come into contact once more, while the blanks are between said faces, to relieve the pressure on said blanks.

3. In an apparatus of the character specified, the combination of a pair of cooperating rolls provided with portions normally in rolling contact with each other and working faces so disposed with reference to the roll axis as to separate said contacting portions when the working faces engage a blank, thereby exerting pressure on said blank, said contacting portions being so formed as to come into contact once more, before the blanks pass from between said faces, to relieve the pressure while the blanks pass from between said faces.

4. In an apparatus of the character specified, the combination of a pair of cooperating rolls provided with portions normally in rolling contact with each other and eccentric working faces so disposed with reference to the roll axis as to separate said contacting portions when the working faces engage a blank, thereby exerting pressure on said blank, said contacting portions having eccentric surfaces so positioned as to contact with each other before the blanks pass from between said faces, to relieve the pressure while the blanks pass from between said faces.

5. In an apparatus of the character specified, the combination of a pair of cooperating rolls each provided with a collar at each end thereof and an eccentric working face between said collars, the collars of each pair of rolls being normally in rolling contact with each other, said working faces being so disposed with reference to the roll axis as to separate said collars when the working faces engage a blank, thereby exerting pressure on said blank, said collars having eccentric portions contacting before the blanks pass from between said faces so as to relieve the pressure while the blanks pass from between said faces.

6. In an apparatus of the character specified, the combination of a pair of cooperating rolls provided with collars normally in rolling contact with each other and eccentric

working faces so disposed with reference to the roll axis as to separate said contacting collars when the working faces engage a blank, thereby exerting pressure on said blank, said collars having eccentric portions contacting before the blanks pass from between said faces so as to gradually shift the pressure from said faces to said collars and relieve the blanks from pressure while they pass from between said faces.

7. In an apparatus of the character specified, the combination of a pair of cooperating rolls provided with collars normally in rolling contact with each other and eccentric working faces so disposed with reference to the roll axis as to separate said contacting collars when the working faces engage a blank, thereby exerting pressure on said blank, and cams carried by said collars and having high points adapted to contact before the blanks pass from between said faces so as to gradually shift the pressure from said faces and relieve the blanks from pressure while they pass from between said faces.

8. In an apparatus of the character specified, the combination of a pair of cooperating rolls, each roll having a cylindrical collar at each end thereof and an eccentric body portion between the collars, said collars being normally in rolling contact with each other, said body portions having working faces so disposed with reference to the roll axis as to separate the contacting collars, when said faces engage a blank, thereby exerting pressure on said blank, and a cam carried by each collar, the high points of said cams contacting with each other at predetermined positions to shift the pressure from said faces and relieve the pressure on said blanks while they pass from between said faces.

9. In an apparatus of the character specified, the combination of a pair of cooperating rolls, each roll having a cylindrical collar at each end thereof, provided with a recess and an eccentric body portion between the collars, said collars being normally in rolling contact with each other, said body portions having working faces so disposed with reference to the roll axis as to separate the contacting collars, when said faces engage a blank, thereby exerting pressure on said blank, and a cam secured in each of the recesses of said collars and projecting slightly above the cylindrical surface of the collar, the high points of said cams contacting with each other at predetermined positions to shift the pressure from said faces and relieve the pressure on said blanks while they pass from between said faces.

10. In an apparatus of the character specified, the combination of a pair of cooperating rolls, each roll having a cylindrical collar at each end thereof, provided with a

recess, and an eccentric body portion between the collars, said collars being normally in rolling contact with each other, said body portions having working faces so disposed with reference to the roll axis as to separate the contacting collars, when said faces engage a blank, thereby exerting pressure on said blank, a wedge positioned in the bottom of each of said recesses and cams 15 5 cured in position upon said wedges and pro-
jecting slightly above the cylindrical surfaces of said collars, the high points of said cams contacting with each other at predetermined positions to shift the pressure from said faces and relieve the pressure on said blanks while they pass from between said faces.

In testimony whereof, I affix my signature.

OTTO C. SCHOENWERK.
